UNITED STATES PATENT OFFICE

127,613

DESIGN FOR A CIGARETTE CONTAINER OR SIMILAR ARTICLE

David W. Dunberg, New York, N. Y.

Application March 13, 1941, Serial No. 99,543

Term of patent 7 years

To all whom it may concern:

Be it known that I, David W. Dunberg, a citizen of the United States of America, residing in New York city, county of New York, and State of New York, have invented a new, original, and ornamental Design for a Cigarette Container or Similar Article, of which the following is a specification, reference being had to the accompanying drawing, forming part thereof.

Fig. 1 is a front perspective view of a cigarette container or similar article showing my new design.

Fig. 2 is a rear perspective view thereof.

Fig. 3 is the same view as that shown in Fig. 1, illustrating the front portion of the cigarette container in open position.

I claim:

The ornamental design for a cigarette container or similar article, as shown.

DAVID W. DUNBERG.
